UNITED STATES PATENT OFFICE.

IRMGARD VON HAXTHAUSEN, OF MUNICH, GERMANY.

DESIGN FOR A RADIATOR ORNAMENT.

Application filed June 1, 1927. Serial No. 22,263. Term of patent 7 years.

To all whom it may concern:

Be it known that I, IRMGARD VON HAXTHAUSEN, a citizen of Germany, and a resident of Munich, Germany, have invented a new, original, and ornamental Design for a Radiator Ornament, of which the following is a specification, reference being had to the accompanying drawing, forming part thereof.

The drawing is a perspective view of a radiator ornament showing my new design.

I claim:

The ornamental design for a radiator ornament substantially as shown.

IRMGARD VON HAXTHAUSEN.
